CLAIM

The ornamental design for a device for respiratory therapy, as shown and described.

DESCRIPTION

FIG. 1 is a perspective view of the device for respiratory therapy of the present invention;

FIG. 2 is an alternative perspective view thereof;

FIG. 3 is a left-side elevational view thereof;

FIG. 4 is a right-side elevational view thereof;

FIG. 5 is a front elevational view thereof;

FIG. 6 is a back elevational view thereof;

FIG. 7 is a top view thereof;

FIG. 8 is a bottom view thereof; and,

FIG. 9 is a perspective view showing the device for respiratory therapy in a condition of use aiding a person undergoing respiratory therapy.

The broken lines shown in the drawings illustrate environmental subject matter and form no part of the claimed design.
